UNITED STATES PATENT OFFICE.

JOHN F. TRITLE, OF SCHENECTADY, NEW YORK, ASSIGNOR TO GENERAL ELECTRIC COMPANY, A CORPORATION OF NEW YORK.

CAR-LIGHTING SYSTEM.

1,262,411.

Specification of Letters Patent. Patented Apr. 9, 1918.

Application filed December 18, 1913. Serial No. 807,448.

To all whom it may concern:

Be it known that I, JOHN F. TRITLE, a citizen of the United States, residing at Schenectady, in the county of Schenectady, State of New York, have invented certain new and useful Improvements in Car-Lighting Systems, of which the following is a specification.

My invention relates to car lighting systems and more especially to devices for preventing a dimming or flickering of the lamps, due to excessive variations in voltage in the source of supply.

Where electricity is used as a motive power for vehicles, it is customary to use the same source of power which supplies the traction motors to also supply the lighting circuits. It is neither necessary nor possible in such power circuits to maintain a constant potential because of the sudden and large variations in load. The consequence is that there is a constant dimming of the lights. Then, too, in those installations where the power is taken from a third rail this rail is broken at intervals, as when crossing another system. These gaps in the third rail are of such an extent that during an interval of two or three seconds no power is supplied to the train, and during this interval the lights will go out. This flickering and dimming is a source of great annoyance to the occupants of the car.

The object of my invention is to provide a device to be used in connection with a car lighting circuit where the same is connected to the main source of supply which will neutralize or avoid the dimming and flickering referred to above. My device preferably consists of a compound wound dynamo electric machine which is connected to the lighting circuit and normally floats as a free running motor on the main source of supply. A suitable relay switch is provided which, upon a failure of the supply current, automatically disconnects this machine from the source of supply so that it pumps back as a generator to feed the lighting circuit so long as its momentum keeps it running. To increase this effect, I provide a fly-wheel upon the machine which stores up kinetic energy and gives it out as required.

Another object of my invention is to so arrange my device that the series and shunt fields will act in conjunction whether the

machine is running as a motor or as a generator. By this arrangement I am enabled to obtain the benefits of the characteristics of a compound generator and an accumulative motor and also avoid the necessity of reversing the flux in the series field every time the machine comes into action as a generator.

A further object of my invention is to arrange my machine so that the series field thereof is automatically shunted by a resistance when it runs as a motor and this shunt removed when it runs as a generator. By such an arrangement the speed of the machine is made as high as is consistent with stability when running as a motor and thereby it is enabled to store up a large amount of kinetic energy for use when the power supply fails.

A further object of my invention is to provide means for automatically opening the circuit between the traction motors and my dynamo electric machine so that this machine can pump back only momentarily through the traction motors and will not try to supply power for running the car. If no such device is provided my machine would be heavily overloaded and perhaps seriously injured as well as failing in its work of sustaining the lights.

The arrangement which I have used will be more clearly understood from an inspection of the accompanying drawing in which Figure 1 is a diagrammatic view showing the circuits and connections used. Figs. 2 and 3 are diagrams showing the resulting connections when the relay switch used is closed and open respectively.

At 1 I have indicated a third rail, such as is commonly used, in which are found gaps 2, such as would occur where the system crosses another system. Contacting with this third rail is the ordinary shoe or trolley 3 through which power is supplied to the traction motor circuit 4 and to the arrangement which constitutes my invention. At 5 is indicated diagrammatically a dynamo electric machine, having one terminal connected to ground, and on the same shaft with which is a fly-wheel 6. This machine is provided with a shunt field winding 7 and a series field winding 8. The lighting circuit which is used for the vehicle is indicated at 9 as having one terminal connected to the

2

ground. At 10 I have shown diagrammatically a reverse current relay of common construction, wherein the shunt winding 11 is connected to the trolley at one terminal and at the other terminal is connected through a resistance 12 to ground. On the same relay there is supplied a series winding 13 which is so wound that it normally acts in conjunction with the shunt winding and serves 5 to hold the core 14 in its raised position. To the relay armature are attached the pivoted switch arms 15 and 16, designed to contact with fixed points 17 and 18 respectively. Between the pivoted points of these contact 10 arms I have bridged a preferably non-inductive resistance 20, the function of which will be later explained. Clearly a resistance having a low inductance could be substituted if desired.

15 20 The operation of my device will be as follows:—When power is being furnished from the third rail 1, the shunt winding 11 of the relay will serve to attract the solenoid and close the switch arms. When the upper 25 switch arm 15 contacts with the fixed point 17, the series winding of the relay will be energized and will help to hold the switch in place. Simultaneously with this the lower switch arm 16 will contact with the fixed 30 point 18 and serve a purpose to be later explained. Since power is now supplied to the dynamo electric machine 5, this machine will run as a motor and will impart kinetic energy to the fly-wheel 6. It should be noted 35 that the connections are so arranged that the series and shunt fields are aiding each other and that the resistance 20 is bridged across the series field 8 when the lower switch arm is closed. This resistance is so de- 40 signed that the excitation of the series field is reduced in order to speed up the motor as far as is consistent with stability. It should also be noted that without such a resistance between the switch arms, the series field 45 would be short circuited and no flux induced thereby. This would be a disadvantage because it would necessitate the building up of the series field when the machine began its action as a generator, and further the ma- 50 chine would not have a series characteristic for starting. The lamp circuit 9 is now connected in parallel to the dynamo electric machine running as a motor and receives power through the series winding of the 55 relay, the switch arm 15, and the resistance 20 and the switch arm 16 in parallel with the series field 8. Suppose, now, that the trolley 3 reaches a gap in the third rail and that consequently no power is being sup- 60 plied to either the traction motors or the lamp circuit. Due to the momentum im- 65 parted to the fly-wheel 6, the dynamo electric machine will continue running in the same direction and will momentarily pump back as a generator through the series wind-

ing of the relay 10. Because of this reversal of current in the series winding, the two windings of the relay will be opposed in their action and the core 14 will drop, opening the switch. Various results are accom- 70 plished thereby. First, the traction motor circuit is cut off from the lighting circuit and the dynamo electric machine. My machine cannot therefore supply power to the traction motors and attempt to propel the 75 vehicle. If it were possible for the machine to so supply power, it would be seriously overloaded, and the particular result which I seek to accomplish would be impossible. Second, the shunt resistance across the series 80 field is removed and it is put in series with the field. It will be noted that, whereas the upper terminal of the machine 5 was connected to the lower terminal of the series field winding 8 through the contacts 16 and 85 18, the opening of the switch leaves the upper terminal of the machine connected to the upper terminal of the series field winding through the resistance 20. Thus, as will be clearly seen by reference to Figs. 2 and 3, 90 the relative connection of said series field winding and said machine has been reversed. This results in causing a flow of current through the series field in the same direction as when the machine was running as a 95 motor and in allowing the full current being generated to flow through said field, thus giving the maximum possible compounding effect. Obviously, because of the momentary delay in the demagnetization of 10 the shunt coil 11 of the relay there will be an instant before the contacts 16 and 18 open when the machine will pump back to the trolley through the parallel circuit formed by the series field winding 8 and the resistance 20. Because of the relative inductance of the two branches, practically all of the current will pass through the resistance 20, but the voltage applied at the terminals of the series field will be reversed. Because of 11 the almost instantaneous operation of the relay, however, and because of the relatively high inductance of the field winding 8, no reversal of flux will occur. Third, it will be seen that the lamp circuit is now 11 connected to one terminal of my dynamo electric machine, and that, because of the ground connections of this circuit and of my machine, a closed circuit is formed whereby the lamps will be supplied with energy. 12 (See Fig. 3.) It should be noted that the compounding action of the two fields is continued while the machine acts as a generator because of the reversal of the connection relative of the series field winding and the brush terminals of the machine and that because of this compounding action the voltage supplied by the machine will be sustained through a considerable drop in the speed thereof. I am thereby enabled to 13

supply the lamp circuit with approximately the desired voltage throughout the whole interval when the trolley is crossing the gap in the third rail.

5 From the above it will be seen that I obtain the objects desired, and that on a failure of power from the main source of supply, my machine will act as a generator to supply power to the lamp circuit and 10 will aid in automatically disconnecting the traction motors from said circuit. It should be further noted that a total failure of power is not necessary to cause the action described above and that should there be a 15 considerable decrease in the voltage of the supply circuit, a similar action would take place. In other words, as soon as the counter-electromotive force generated in my machine exceeds the voltage impressed thereon 20 from the outside source, it will cause current to flow in the reverse direction with the result that the relay switch will drop out and the lamps be supplied from this machine instead of from the supply circuit. 25 This action will tend to avoid constant variations in the brilliancy of the lamps which is so often caused by the great variations in voltage in the supply circuit.

I conceive that my device might be employed for other purposes than that herein described and that various modifications of the particular arrangement might be employed which would accomplish the same result. I, therefore, aim in the appended 35 claims to cover all such modifications which come within the spirit of my invention.

What I claim as new and desire to secure by Letters Patent of the United States, is:—

40 1. In combination across a source of supply, a dynamo electric machine having a series field winding, a lamp circuit in parallel with the armature of said machine, and means responsive to a failure of the 45 supplied current for connecting the lamp circuit and the series field in series in a shunt to the armature of said machine so that the flux in said field is in the same direction whether the machine runs as a motor 50 or as a generator.

2. The combination of a source of supply with a closed circuit comprising an electrical load and a dynamo-electric machine with its series field winding, one side 55 of said load being permanently connected to one side of said source of supply, a removable connection, from the conductor joining said series field winding and said machine, to the other side of said source 60 of supply, and means responsive to the direction of the flow of current between said source and said circuit for controlling said last named connection.

3. In combination, a source of supply, 65 translating devices energized from said

source, the said devices comprising an electrical load and an accumulatively compound wound dynamo-electric machine operating as a motor, automatic switch mechanism controlling the said devices, and connections 70 whereby the said machine operates as an accumulatively compound wound generator supplying energy to the said load when the switch mechanism opens.

4. In combination, a source of supply, an 75 electric load and a dynamo-electric machine having a shunt and a series field, a shunt for the series field winding, automatic means controlling the said shunt, and connections whereby the said load and the said machine 80 operating as an accumulatively compound wound motor are energized from the source of supply or the said machine operates as an accumulatively compound wound generator 85 supplying energy to said load, depending on the operation of the said automatic means.

5. In combination, a source of supply, translating devices energized from said source, the said devices comprising an electrical load and a dynamo-electric machine having a series field winding, and means responsive to the direction of current flow between said source and said machine for reversing the relative direction of the field 90 and armature currents of said machine and supplying the electrical load with energy from the said machine.

6. The combination with a dynamo-electric machine having a series field winding, 100 of an electrical load connected in series to the said field in a shunt circuit to the armature of said machine, a source of supply, and means energized from the source of supply for establishing a bridging connection around the series field and connecting the said machine and load to the source of supply.

7. The combination with a dynamo electric machine having a series field winding, 110 of an electrical load connected in series with the said field in a shunt circuit to the armature of said machine, a source of supply, and automatically operated electromagnetic switch mechanism for connecting the said 115 load and machine to said source with the series field of said machine shunted.

8. The combination with a dynamo-electric machine having a series field winding, 120 of a resistance and an electrical load connected in series with the said field winding in a shunt circuit to the armature of said machine, a source of supply, and means energized from said source for connecting the said machine to said source with the series 125 field shunted by said resistance and the said load connected in shunt to the armature of said machine.

9. In combination, a source of supply, translating devices energized from said 130

source, the said devices comprising a dynamo-electric machine having a series field winding and an electrical load connected in shunt to the armature of said machine, a shunt for the said field winding, and means responsive to the direction of current flow between said source and said machine for controlling the said shunt, the direction of the flow of current through the said field winding, and the connection of said devices to said source.

10. The combination with a dynamo-electric machine having a series field winding, of an electrical load connected in series with the said field in a shunt circuit to the armature of said machine, a source of supply, electromagnetic switch mechanism having an operating coil energized from said source for connecting the said machine to said source with the series field shunted and the electrical load connected in shunt to the armature of said machine, and means energized responsively to the flow of current

from said machine to said source for opening the said switch mechanism. 25

11. In combination a source of supply, translating devices energized from the said source, the said devices comprising a traction circuit, an electric load, and an accumulatively compound-wound dynamo-electric machine, means responsive to the direction of current flow between said source and said machine for dis-connecting the said machine and the said load from the traction circuit and the source of supply, and connections 30 whereby the said machine, dis-connected from said source, operates as an accumulative compound-wound generator supplying energy to said load.

In witness whereof, I have hereunto set 40 my hand this 17th day of December, 1913.

JOHN F. TRITLE.
